UNITED STATES PATENT OFFICE.

RAFAEL M. ANDREU, OF HABANA, CUBA.

PENHOLDER.

1,173,701.

Specification of Letters Patent. Patented Feb. 29, 1916.

Application filed June 16, 1915. Serial No. 34,467.

To all whom it may concern:

Be it known that I, RAFAEL M. ANDREU, a citizen of the Republic of Cuba, residing at Habana, Island of Cuba, have invented certain new and useful Improvements in Penholders, of which the following is a specification, reference being had to the accompanying drawings.

My present invention relates to new and useful improvements in pen holders and as its principal object aims to provide a device of this character which is so constructed that the pen points used in the holder may, after becoming corroded with ink or otherwise rendered unfit for use, be easily and quickly ejected from the holder, without requiring that the operator directly grasp the pen point itself.

A further and more specific object of the invention is to provide a pen holder of this character which includes as its essential elements of construction, a stem or staff, a fixed sleeve, which is secured upon the terminal of the stem or staff, a second sleeve which is slidable upon the fixed sleeve and is adapted to clamp the inner end of the pen point upon the end of the staff, and spring members which are disposed between the fixed sleeve and movable sleeve for limiting the movement of this latter member toward the end of the staff, to permit the sleeve to be moved away from the end of the staff when the pen point is to be removed.

Another and general object of the invention is to provide a pen holder which possesses the above characteristics but is, at the same time, relatively simple in construction so that it may be cheaply manufactured.

The above, and other incidental objects of a similar nature, which will be hereinafter more specifically treated are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention, as it is reduced to practice, and throughout the several views of which similar reference numerals designate corresponding parts, Figure 1 is a longitudinal section taken through the fixed and movable sleeves which constitute the

pen holding device, showing the sleeves applied to a staff or stem, which is shown in full lines; Fig. 2 is a composite view showing the fixed sleeve applied to the staff and the movable sleeve removed from the fixed sleeve; and Fig. 3 is a section on the line 3—3, of Fig. 1.

As embodied in the accompanying drawings, the pen holder of the present invention preferably includes a stem or staff 10 of conventional design; a fixed sleeve 11, which is mounted upon the end of the staff and projects some distance therebeyond; a slidable sleeve 12, which is mounted upon the fixed sleeve; stop springs 13, which are disposed between the fixed and movable sleeves, for limiting the outward movement of this latter member; and a fixed annular stop 14 which is formed at the inner end of the fixed sleeve for limiting the inward movement of the movable sleeve.

The fixed sleeve 11 is preferably formed from a single blank of sheet metal and is, as shown in Fig. 1 tubular in shape. The inner end of the sleeve is open and is slipped over the staff. The stop member, heretofore designated by the numeral 14 is formed as shown in Fig. 1 on the inner end of this sleeve and is adapted to limit the inward sliding movement of the movable sleeve, in a manner which will hereinafter become apparent. The outer end of the fixed sleeve projects a considerable distance beyond the terminal of the staff and is preferably provided with slits or kerfs 15 which release resilient gripping tongues 16.

At diametrically opposite points, the fixed sleeve is, as best shown in detail in Fig. 2 provided with pairs of parallel longitudinal slits 17 and transverse slits 18. A slit 18 is formed at one end of each of the spring tongues 19 defined by the parallel slits to release these members 19 from the sleeve. As is shown in Fig. 1 the two spring tongues are directed outwardly and are terminally bent to form the inwardly extending lugs 20.

The sleeve 12 is provided with an internal annular groove 21, the one wall of which indicated at 22, extends at right angles to the longitudinal axis of the sleeve and the other wall 23 of which extends at an acute angle thereto. The angle which the wall 23 bears to the wall 22 corresponds to the angle of the tongues 21 to the lugs 20.

Referring now to Fig. 1 it will be readily

observed that when the movable sleeve is set upon the fixed sleeve, the spring tongues seat within grooves and bear against the inclined wall 23 thereof, while the lugs of the 5 springs are adapted to seat against the wall 22 of the groove. Thus the spring tongues and their lugs serve to prevent the withdrawal of the movable sleeve from the fixed sleeve, after the movable sleeve has once 10 been applied thereto. At the same time, it will be observed that the movable sleeve may be slid inwardly, without hindrance, since the spring tongues will be moved inwardly into the sleeve 11 by the inclined 15 wall of the movable sleeve. When a pen point is to be inserted in my pen holder, the bowed portion of the pen is inserted between the gripping jaws 16 and the outer end of the sleeve 12 in the same manner as though 20 the pen point were applied to an ordinary pen holder. When the pen is to be removed from the pen holder, the sleeve 12 is moved inwardly on the sleeve 11. The spring tongues 13 move inwardly in the manner 25 previously explained to permit such inward movement of the sleeve 12. The inward movement of the sleeve 12 will obviously uncover the outer end of the fixed sleeve 11 and as a result the bowed portion of the pen 30 point will be uncovered and the pen, therefore, allowed to drop from the pen holder.

I now desire to particularly explain that while springs of the type shown in the accompanying drawings are preferably employed, I do not wish to limit myself to this 35 specific construction, since it is obvious that different types of springs may be substituted for those shown, without departing in any way from the spirit of the invention. It 40 is only essential that the springs be so designed and related to the movable sleeve that they will limit the outward movement of this member on the movable sleeve, but will permit the movable sleeve to be readily 45 withdrawn from engagement with the pen point, so that this member may be removed from the pen holder. In this connection, it 50 will be obvious that the springs may be carried by the movable sleeve and arranged for engagement with the fixed sleeve, instead of being oppositely arranged, as in the accompanying drawings.

It will also be apparent that the spring

tongues may be formed as separate elements and riveted, soldered, or otherwise suitably secured to the member 11.

By forming the sleeve 12 with an annular groove it is possible to rotate the sleeve 12 while at the same time it is retracted. By this means any sticking of the sleeve 12 to 60 the pen by reason of the drying up of ink therebetween may be overcome and the sleeve 12 readily disengaged from the pen 6. Where the sleeve 12 is only reciprocatable the ink often dries and prevents the 65 withdrawal of the sleeve without considerable force being exerted.

In reduction to practice, it has been found that the form of this invention illustrated in the drawings, and referred to in the above description as the preferred embodiment is the most efficient and practical; yet realizing that the conditions concurrent with the adoption of this device will necessarily vary, it is desirable to emphasize the 75 fact that various minor changes in the details of construction, proportion and arrangement of parts may be resorted to, when required, without sacrificing any of the advantages of this invention, as defined 80 by the appended claim.

What is claimed is:—

A pen holder including a staff, a sleeve fixed upon one end thereof, stop tongues carried by the sleeve and extending rearward and outward therefrom, a sleeve movable upon the fixed sleeve and being of less length than the fixed sleeve and adapted to clamp the butt of a pen point against the outer end of the pen, said movable portion being provided with an internal annular groove, said stop tongues being engageable in the groove for limiting the outward movement of the movable sleeve and being depressed by the movable sleeve when the same is moving away from the forward end of the fixed sleeve, the annular groove permitting rotary movement of the movable sleeve upon the stop tongues and upon the fixed sleeve.

In testimony whereof I hereunto affix my signature in the presence of two witnesses.

RAFAEL M. ANDREU.
